SPRING HINGE

Clifford Harrison Wasson and Louis Dean Neer,
Indianapolis, Ind., assignors to Nik-O-Lok
Company, Indianapolis, Ind., a corporation of
Indiana

Application March 24, 1947, Serial No. 736,836

1 Claim. (Cl. 16—128)

1

The present invention relates to hinges, and is particularly concerned with improvements in spring hinges. In many installations, it is highly important to hang doors, gates, and the like, in such a fashion that they shall not sag, regardless of the use, and abuse, to which they are subjected. One type of such installation is the doors on public toilet booths. Such doors are subjected to extremely rough usage, frequently amounting to vandalism, and if such a door begins to sag, it will frequently fail to latch or lock when permitted to swing to closed position under the influence of its spring hinges. Hinges heretofore in use have been so constructed that the parts thereof will bend or tear under abuse. Such hinges, as heretofore known, have also been subject to other disadvantages, including improper support and anchorage of the springs, which produces binding of the springs if they are wound tightly enough to insure closure and latching under all circumstances.

To overcome the above and other disadvantages of known constructions, we have designed a novel spring hinge assembly which lends itself to inexpensive manufacture, simple installation, both in new organizations and in substitution for hinges previously used, and ready repair.

It is a primary object then, of the present invention, to provide an improved hinge construction, overcoming the defects and disadvantages of previously known structures, and introducing new advantages in installation and maintenance.

To the accomplishment of the above and related objects, our invention may be embodied in the form illustrated in the accompanying drawings, attention being called to the fact, however, that the drawings are illustrative only, and that change may be made in the specific construction illustrated and described, so long as the scope of the appended claim is not violated.

Fig. 1 is a perspective view of a hinge constructed in accordance with our invention;

Fig. 2 is a plan view thereof, the operating parts being shown in central longitudinal section;

Fig. 3 is an end view of a spring used in the invention; and

Fig. 4 is a transverse section taken substantially on the line 4—4 of Fig. 2, and looking in the direction of the arrows.

Referring more particularly to the drawings, it will be seen that I have illustrated an imperforate hinge leaf 10 formed to provide, adjacent one end thereof, a laterally projecting ear 11

provided with a central threaded perforation 12 therethrough. The outer surface of the ear is shallowly counterbored around the perforation 12, as indicated at 13, for a purpose later to appear.

Adjacent its opposite end, the leaf 10 is provided with a similar ear 14 formed with a central threaded perforation 15 which is coaxial with the perforation 12. On its outer surface, the ear is shallowly counterbored at 16 to correspond with the arrangement of the ear 11.

A second imperforate hinge leaf 17 is formed with a laterally projecting barrel 18 internally bored as at 19, said barrel being adapted to be arranged between the ears 11 and 14 with its bore coaxial with the perforations 12 and 15.

A journal element 20 is formed with a body 21 snugly receivable in one end of the barrel 18, in the manner illustrated, and said element is provided with an enlarged head 22 which overlies said end of the barrel, the outside diameter of said head being substantially equal to the outside diameter of the barrel and of the ear 11, said head being interposed between the adjacent end 25 of the barrel and said ear. Axially, the head 22 is formed with an outwardly opening socket 23 in which is preferably snugly received a bushing 24, which may preferably be made of cadmium-plated steel.

30 A second journal element 25 comprises a body 26 snugly receivable in the opposite end of the barrel 18, and an enlarged head 27 whose outside diameter is substantially equal to that of the barrel 18 and that of the ear 14, said head 27 35 being interposed between the adjacent end of the barrel and said ear 14. Axially, the head 27 is formed with an outwardly opening socket 28 in which is preferably received a bushing 29 similar to the bushing 24.

40 A coiled spring 30 is axially positioned within the barrel 18 between the journal elements 20 and 25. The element 20 is formed with an internal projection 31 over which is sleeved one end of the spring 30; and said extension is diametrically slotted, as at 32, to receive an integral tongue 33 at said end of the spring, said tongue being diametrically located with respect to the body of the spring and preferably extending substantially throughout a complete diameter of said spring. The element 25 is provided with a similar extension 34, similarly slotted at 35, to receive a tongue 36 parallel but oppositely projecting with respect to the tongue 33 and located at the opposite end of the spring. Because of the location of the tongues 33 and 36, and because of the

fact that they extend substantially throughout the diameters of the spring body, relative rotation between the elements 20 and 25 exerts a purely torsional effect upon the spring without exerting any tendency thereupon to "cock" the spring, or throw any portion thereof out of proper axial alignment. As a consequence, there is no tendency for the spring to bow into frictional engagement with the barrel 18. Such an action, which occurs in many springs of the prior art with which we are familiar, causes a binding between the elements of the hinge to prevent proper smooth action of the hinge when the leaves thereof are relatively moved about the pivotal axis.

A flat, spring steel washer 37 is preferably interposed between the head 22 of the element 20 and the ear 11; and a pivot pin 38 threadedly penetrates the ear 11 and washer 37, an unthreaded extension 39 thereof being seated in bushing 24. Said pin is provided with an enlarged head 40 which, when the pin is properly seated, bears against a "shake-proof" washer 41 whose axial dimension is only slightly greater than the depth of the counterbore 13, and whose external periphery is substantially equivalent to the periphery of the counterbore 13. Similarly, a washer 42 like the washer 37 is interposed between the element 25 and the ear 14, and a pivot pin 43 threadedly penetrates the ear 14 and is provided with an unthreaded extension 44 seating in the bushing 29. The head 45 of the pin 43 engages a washer 46 like the washer 41, seated in the counterbore 16.

The head 22 of the element 20 is formed with a plurality of radial, peripherally spaced bores 47 opening through the exposed external surface of the head 22. Any one of said bores may be selected to receive a stop pin 48 which will bear against the surface of the leaf 10 to force the element 20 to move rotationally with the leaf 10. The body 26 of the element 25 is formed with a radial tooth or projection 49 engageable in a slot 50 formed in the internal surface of the barrel 18. Thereby, the element 25 is rotationally anchored to the leaf 17. Tension may be applied to the spring 30 by rotating the element 22 through the use of a suitable tool engageable in the bores 47; and when a proper degree of tension has been applied to the spring, the pin 48 will be entered in that bore 47 nearest the surface of the leaf 10. When, now, the element

20 is released, the pin 48 will be pressed against the surface of the leaf 10.

It is to be noted that we have stated specifically that the leaves 10 and 17 are imperforate. This is for the reason that, in many cases, it is desirable to substitute our new hinge for hinges previously installed. Frequently, such hinges are mounted upon glass, tile, or concrete walls, and it is highly desirable that anchoring screws enter the existing holes. We leave the hinge leaves imperforate, in manufacture, in order that, for any given installation, holes may be drilled therein to conform to existing screw holes in the walls upon which the hinges are to be installed.

We claim as our invention:

A hinge comprising a pair of leaves, one of said leaves being provided with a laterally-projecting ear adjacent each end, said ears being provided with aligned, threaded perforations therethrough, the other of said leaves being provided with a laterally-displaced barrel, the bore of said barrel being adapted to assume a position between said ears and coaxial therewith, a journal element for each end of said barrel, each journal element comprising a base portion snugly receivable in an end of said barrel and a head portion overlying such barrel end and having an outside diameter substantially equal to that of said ears, the outer end of each journal element being provided with an outwardly-opening axial socket, a bushing received in each of said sockets, said bushings being coaxial with said ear perforations, and a pivot pin threadedly penetrating the perforation of each ear and having an unthreaded extension seated in the bushing of the associated journal element.
